Primary Examiner — Dana L Meyrow(74) *Attorney, Agent, or Firm* — Dinsmore & Shohl LLP(57) **CLAIM**

The ornamental design for a squeezable dip bottle, as shown and described.

DESCRIPTION

FIG. 1 is a top, front perspective view of a squeezable dip bottle showing my new design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The broken lines in the drawings illustrate the portions of the squeezable dip bottle that form no part of the claim.
